UNITED STATES PATENT OFFICE.

CHARLES K. STINSON, OF BOSTON, ASSIGNOR TO LEVI LADD, OF NEEDHAM, MASSACHUSETTS.

CLOTHES-WRINGER.

SPECIFICATION forming part of Letters Patent No. 327,616, dated October 6, 1885.

Application filed August 20, 1884. Serial No. 141,042. (Model.)

To all whom it may concern:

Be it known that I, CHARLES K. STINSON, a citizen of the United States, residing at Boston, in the county of Suffolk and State of Massachusetts, have invented certain new and useful Improvements in Clothes-Wringers; and I do hereby declare that the same are fully described in the following specification, and illustrated in the accompanying drawings.

- 10 This invention is in the nature of an improvement upon that set forth in my Patent No. 287,782, granted October 30, 1883. In my patented machine the frame pieces at each end were pivoted to one member of the clamping-jaws, and the parts were so arranged that both the tub-pressure and the roller-pressure were applied and relaxed by tipping the machine forward and back upon the pivots by which it was attached to its clamps.
- 15 In my present improvement the same result is obtained by a similar movement; but instead of pivoting the end frames to the clamps direct I connect one of the clamp-jaws by a terminal ring bearing with the shaft of the lower roller, and I form at the upper extremity of the other jaw, pivoted to the first, a laterally-projecting stud, which engages with a shoulder or recess in the end frame, and thereby I apply both the pressures simultaneously.
- 20 The lower roller-shaft becomes thus the center of motion, for one clamp-jaw is pivoted upon it, and the upper roller, cross-bar, springs, and end frames move in a curved line, approximately an arc, around said shaft in applying or relaxing the pressures.

The action of the parts is more fully explained in the following description, in which subordinate features of my invention are also set forth.

- 25 In the drawings, Figures 1 and 2 represent the two jaws of one pair of clamps detached from the machine and from each other. Fig. 3 shows the parts arranged in position for use, the view showing the inner face of the end frame, the roller-journals and cross-bar being in section and the position of the rollers suggested by dotted lines. Fig. 4 is an inside view of one of the end frames, a part broken away. Fig. 5 is an end elevation showing

the rolls tipped down, as when pressure is relaxed. Fig. 6 is a longitudinal section through the roller-bearings.

A is the shaft of the lower roller, *a*, and B that of the upper roller, *b*.

C C are the end frames, connected transversely by the cross-piece D, by which the clothes are received and delivered from the tub after passing between the rollers.

E E are curved steel springs secured at their lower ends to the end frames and cross-bar, and at their free ends forming bearings *e* for the journals of the upper rollers.

The two clamp-jaws F G are pivoted to each other, preferably by a cylindrical stud, H, formed on the outermost jaw, G, and projecting inwardly through the corresponding aperture, *h*, in the short jaw F. These studs may be considerably prolonged and enter the ends of a tube placed parallel to the rollers and between the clamps, so as to keep the studs in line axially. Instead of this arrangement, a rigid rod passing loosely through the short jaws may connect the outside clamp-jaws for the described pivotal movement.

The shorter clamp-jaw, F, has a sleeve or ring bearing, *f*, formed at its upper end, to receive the journal A of the lower roller. When this sleeve is broad, it is alone sufficient to keep the pivot H in true axial position without the rod or tube above referred to. The sleeve *f* also serves to keep both the clamps in proper relation to the shaft A. The other jaw, G, which presses against the exterior of the tub, has at its upper end and beyond the stud H an outwardly-projecting lug, L, which works in a slot or recess or against a rib or shoulder, K, on the inner face of the end frame. This recess or shoulder is preferably of the cam form, (best shown in Fig. 4,) and is at or near its middle portion considerably higher than at its end *k*, so that the clamp-jaws will be lifted (or the end frames drawn down) by the tilting movement of the frames upon the journals A, which work in vertical slots in the frame-pieces C, while the lugs L are engaged with the recesses or shoulders K. By this engagement of the lug L and shoulder K the springs are put under tension, the rollers

are pressed hard together, and the pivoted clamp-jaws grasp the edge of the tub tightly whenever the machine is tipped back from the relaxed position of Fig. 5 to the upright working position of Fig. 3, and these pressures are released by the reverse movement of the machine—that is, by again tipping it down toward the center of the tub into the position shown in Fig. 5, in which position it is readily applied to and released from the tub. In these tipping movements the lug L traverses the recess or shoulder K from the end k most remote to and a little past the center or point of greatest pressure. The two clamp-jaws being pivoted to each other by the stud H, and being linked to the roller-shaft by the ring f at one end of one jaw, the two pressures desired are obtained simultaneously by the movement specified. When pressure is relaxed, both rollers drop downward a little, the journals B of the upper roller resting then upon the upper edges of the frames C C, which support it against the spring-pressure, while the lower roller drops slightly farther to be free from pressure.

I claim as my invention—

1. In a clothes-wringer, two yielding rollers with suitable springs and two end frames connected by a cross-bar, in combination with clamping devices consisting of two jaws pivoted to each other, one of said jaws having its upper end formed as a ring or strap embracing the journal of the lower roller, while

the other at its upper end has an outward projection bearing against a shoulder on the end frame, for the purpose set forth.

2. In combination with the rollers and end frames of a clothes-wringer, a clamping device at each end of the machine formed in two parts pivoted to each other by means of a stud cast upon one member of each pair of clamps and passing loosely through the other member, said clamps and end frames being both pivoted upon the journals of the lower roller, substantially as and for the purpose set forth.

3. In combination with the rollers and frame of a clothes-wringer, a clamping device in two parts pivoted to each other, one of the clamp-jaws having a cylindrical stud cast upon it forming a pivot for the other jaw, and also having an outward projection cast upon it to engage with a shoulder or recess of the end frame, substantially as set forth.

4. In a clothes-wringer, a clamping device consisting of two jaws pivoted to each other, one of said jaws having cast upon its upper end an outwardly-projecting lug, L, in combination with the end frames provided with the shoulder K, substantially as set forth.

In testimony whereof I hereto affix my signature in presence of two witnesses.

CHARLES K. STINSON.
